UNITED STATES PATENT OFFICE.

JOHN H. ASHTON, OF PROVIDENCE, RHODE ISLAND.

SELF-CLOSING VALVE.

1,068,556.

Specification of Letters Patent.

Patented July 29, 1913.

Application filed September 12, 1911. Serial No. 648,869.

To all whom it may concern:

Be it known that I, JOHN H. ASHTON, a citizen of the United States, residing at Providence, in the county of Providence and 5 State of Rhode Island, have invented certain new and useful Improvements in Self-Closing Valves, of which the following is a specification.

My present invention relates to adjustable 10 self-closing valves proper, and it consists in the novel construction and arrangement of parts, all as hereinafter set forth and claimed.

In valves embodying my improvement, 15 the parts, when assembled, are readily removably mounted in suitable bodies and employed, as the case may be, in connection with sanitary drinking fountains, globe or stop valves, bibb or faucet cocks, gage cocks, 20 compression valves, &c.

The valve part proper is adapted to be manually opened against the head or pressure of the fluid or water leading to and from it, and is automatically closed by the 25 force or pressure of the fluid itself, the opening force being then removed. By means of my invention the device is adapted for use in a greater variety of valves; it is quick-opening, and it is capable of being 30 more readily and accurately adjustable with respect to the degree of opening or inflow as compared with other self-closing valves. The valve-stem is screwless and is adapted, in coöperation with an interlocking stationary cam-shaped member to easily and positively uncover the valve-seat by a direct push upon the valve-stem or by turning the latter a short distance axially in either direction.

40 In the accompanying sheet of drawings, Figure 1 represents a side elevation of a valve device embodying my improvement, detached from its chambered body or casing, corresponding with the closed position; Fig. 45 2 is a central longitudinal sectional view of the same, but showing the valve open a pre-adjusted amount; Fig. 3 is a side elevation of the relatively stationary inner member having its wall provided with a cam-shaped

opening; Fig. 4 is an end view of it; Fig. 50 43 represents the latter slightly modified; Figs. 5, 6, 7, 8, and 9 represent, in reduced scale, side views of the device in the closed position and mounted in various types of chambered bodies or casings, the latter being 55 sectionally shown.

The improved device A as a whole, capable of being removably screwed into a suitable casing or body, is represented most clearly in Figs. 1 and 2. It consists essentially of the movable valve-stem member carrying a wheel *w* at one end and a valve *v* at the other; a stationary, laterally apertured plug member *a* having the valve-stem extending longitudinally through it and terminating in a seat *a*³ for the valve *v*, and also adapted to be screwed into a suitable body or casing member, the latter having a seat *s*¹ against which, when the device is mounted in the body, the plug is adapted to 70 bear. It further comprises an annular member *b* screwed into said plug, bored to receive the valve-stem, and having one end recessed for holding suitable packing, *f*, the opposite end portion *b*² being cam-shaped, and means 75 for adjusting or positively controlling the amount of valve-opening, as desired. The said stationary hollow or annular plug member *a* has one end portion *a*⁶ hexagon-shaped and screw-threaded, its other end *a*¹ 80 being preferably slightly beveled or cone-shaped to form a seat *a*³, and having a narrow extension *a*⁴ for the metal valve proper *v* and its packing *p* of leather or other suitable material, recessed at *p*¹ to receive said 85 extension when the valve is closed. The barrel part *a*² intermediate said end portions is or may be reduced in diameter and provided with one or more lateral openings *a*⁵ in its wall for the outflow of water, or 90 other fluid, when the valve is open, all as clearly shown in Fig. 2.

The valve-stem has a hand-wheel *w*, or other analogous member, secured to its outer or upper end. Upon manually pushing or 95 turning it, or a combination of both movements, as the case may be, the valve is readily unseated or opened, as will be later

explained. The opposite end portion d^3 of the valve-stem is reduced in diameter to receive the valve v and the valve-holding nuts e . The valve itself may also be bored to receive the collar part d^2 of the valve-stem; the inner edge of the collar extends into the said small annular recess p^1 and also into the bore of the extension a^4 when the valve is seated. Intermediate said collar d^2 and part d , both being of substantially the same diameter, the stem is reduced in size, as at d^1 , to permit ample area between it and the inner surface of the said apertured wall a^2 for the passage of water. At or near the inner end portion d the valve-stem is provided with a pin i fixed transversely therein, the same extending through opposite sides of the stem and capable of engagement with the sides c of the cam or wedge-shaped opening formed in the inner end part of the barrel portion b^2 of the said stationary annular member b . This last-named member b is fitted at b^1 and b^2 to the interior of plug a , and also bored at b^3 to receive the movable valve-stem; the part b^1 is also bored or recessed at b^4 to receive suitable packing material f to prevent leakage around the valve-stem. The packing may have a helical spring s bearing against it and the end of a stop-nut or adjusting member n fitted to the screw-threaded barrel portion b^1 , as clearly shown. In practice the member n and check-nut n^1 are adjusted so as to limit the valve-opening any desired amount, as indicated at t Fig. 1. Fig. 2 represents the valve thus opened.

It is obvious now that a direct push of sufficient force or pressure upon the operating element w , secured to the valve-stem, opens the valve v to permit the inflow of fluid, assuming, of course, that the device A is first mounted in a chambered casing or body member connected to suitably arranged inlet and outlet pipes, and normally seated against seat s^1 . It is evident also that upon turning the handle w a short distance in either direction (see arrows x Fig. 2) the frictional engagement of pin i with the corresponding sides of the cam opening c serves to impart additional leverage to the valve in opening the latter against the pressure of the intake water or fluid.

Fig. 4 $\frac{1}{2}$ represents a slightly modified form of the cam. In this case the valve and its stem can be turned only in one direction to open the valve.

The following is a description of various uses or applications of my improved self-closing valve device A:—In Fig. 5 it is represented as screwed into the body of a sanitary drinking fountain B, provided with inlet and waste pipes h , h^1 , and outlet or discharge nozzle x^1 , the annular collar a^1 of plug a being fitted to an annular seat s^1 of

the said body. In Fig. 6 the device is shown 65 screwed into a casing of the globe valve type, C, provided with inlet and outlet nozzles h^2 , h^3 , and internal annular seat s^1 . Fig. 7 represents the device removably mounted in a bibb-cock or faucet D having inlet and 70 outlet ducts h^4 , h^5 , and internal annular seat s^1 . It may also have a bottom nozzle and plug w^1 . Fig. 8 shows its application to a gage-cock E, the latter having an inlet nozzle h^6 , an outlet or discharge nozzle h^7 and 75 seat s^1 for the annular plug's collar a^1 , and Fig. 9 represents a slight change in the device A in order to adapt it to be employed as a compression valve H. In this arrangement the main body or casing is provided 80 with inlet and outlet nozzles h^8 , h^9 , a valve seat s^1 , a valve proper v^1 , and spring v^2 , the latter in this case serving to automatically close the valve. In this adaptation of the device the cam-opening c is reversed. The 85 valve-opening is attained by moving the stem d outward, or in the arrow direction, its limit of movement being arrested by the engagement of pin i with bottom k of cam-opening. 90

I claim as my invention and desire to secure by U. S. Letters Patent:—

1. In a valve of the self-closing type, provided with a chambered body or casing having an intake and a discharge nozzle and an 95 interior partition dividing the chamber, said partition having an opening therethrough forming a valve-seat, the combination therewith of a laterally apertured barrel member having a central opening throughout its 100 length adjustably mounted in said body, the inner or lower end of the barrel member being annular and fitted to said seat, a manually actuated longitudinally movable rod or stem passing freely through said opening, a 105 valve proper fixed to the inner end of the rod and normally closing the said seated annular end of the barrel, an annular member adjustably mounted in the opposite end portion of the said barrel member having said 110 movable rod extending centrally therethrough, and means arranged to coöperate with the rod and the said annular member to assist in opening the valve, the latter automatically closing by means of the fluid 115 pressure thereagainst when the opening pressure is released.

2. In a self-closing valve, the combination with a chambered body having inlet and outlet openings and an inner partition provided 120 with a valve seat, of an apertured main annular member removably secured in said body having its lower end fitted to said seat, a normally stationary second annular member adjustably movable in an endwise direction in the main annular member having a V-shaped opening formed in its wall, a valve-stem movably mounted in and extend- 125

ing through both the said annular members, a valve secured to its lower end and arranged to close against the corresponding end of the main annular member, lugs extending laterally from the valve-stem in normal engagement with said V-shaped opening, constructed and arranged whereby the

5 imparts angular movement to it for unseating the valve.

In testimony whereof I have affixed my signature in presence of two witnesses.

JOHN H. ASHTON.
